(57) **CLAIM**

The ornamental design for a lamp, as shown and described.

DESCRIPTION

FIG. 1 is a front and top perspective view of a lamp, showing my new design where the shoe laces are in a first position; FIG. 2 is another front and top perspective view thereof where the shoe laces are in a second position;

FIG. 3 is a front perspective view where the shoe laces are in a first position;

FIG. 4 is a rear perspective view where the shoe laces are in a second position;

FIG. 5 is a left side perspective view where the shoe laces are in a first position;

FIG. 6 is a right side perspective view thereof;

FIG. 7 is an enlarged top perspective view thereof; and, FIG. 8 is an enlarged bottom perspective view thereof.
